UNITED STATES PATENT OFFICE.

GEORGE W. MCGILL, OF RIVERDALE, NEW YORK.

DESIGN FOR A PAPER-FASTENER.

SPECIFICATION forming part of Design No. 16,548, dated February 23, 1886.

Application filed January 18, 1886. Serial No. 188,987. Term of patent 14 years.

To all whom it may concern:

Be it known that I, GEORGE W. MCGILL, a citizen of the United States, residing at Riverdale, in the city and county of New York, State of New York, have invented and produced a new and original Design for a Fastener, of which the following is a specification.

The nature of my invention is fully represented in the accompanying drawings, forming part of this specification; and it consists of the parts A B, raised or "struck up" in scallop-like configuration, the projecting part d, and loop-like portion e. The parts A B are correspondingly formed and spread in opposite directions, and are connected together by the loop-like portion e.

In the drawings, Figure 1 shows the design opened out flat. Fig. 2 is a perspective view

of the design, showing its appearance when folded ready for use; and Fig. 3 is an edge view of it, showing its appearance when applied or put in use as a paper-fastener, as intended.

What I claim as my invention, and desire to secure by Letters Patent, is--

The design for a fastener herein shown and described, the same consisting of the parts A B, having a raised scallop-like configuration, the projecting part d, and the loop-like portion e.

In testimony whereof I affix my signature in presence of two witnesses.

GEORGE W. MCGILL.
